Des. 230,005

Patented Jan. 22, 1974

230,005

COMBINED CAN OPENER AND KNIFE SHARPENER

Harold Weiss, Fort Lee, N.J., assignor to Van Wyck International Corporation, New York, N.Y.

Filed June 29, 1972, Ser. No. 267,617

Term of patent 14 years

Int. Cl. D7—99; D8—05

U.S. Cl. D8—35

FIG. 1 is a perspective, viewed from the front of a combined can opener and knife sharpener, showing my new design;

FIG. 2 is a perspective, viewed from the rear thereof;
FIG. 3 is a top plan view thereof.

I claim:

The ornamental design for a combined can opener and knife sharpener, as shown.
